UNITED STATES PATENT OFFICE

104,665

DESIGN FOR A RIDING BOOT

Moe Jacob, New York, N. Y.

Application April 13, 1937, Serial No. 68,733

Term of patent 7 years

To all whom it may concern:

Be it known that I, Moe Jacob, a citizen of the United States and resident of New York city, in the county of New York and State of New York, have invented a new, original, and ornamental Design for a Riding Boot, of which the following is a specification, reference being had to the accompanying drawing forming part thereof, in which,

Fig. 1 is a front view of the boot, showing my new design, and

Fig. 2 is a side view of the boot shown in Fig. 1.
I claim:

The ornamental design for a riding boot as shown.

MOE JACOB.
